J. C. BURGESS.
RAIL TIE AND FASTENER.
APPLICATION FILED AUG. 2, 1915.

Patented Nov. 9, 1915.

Fig. 1.

Fig. 2.

Fig. 3.

Fig. 4.

A technical drawing of a bridge structure, labeled 'Fig. 5.' at the top. The drawing shows a bridge with a central support and two spans. Various dimensions are indicated: 30' and 35' for the left span, 32' for the central section, 36' for the right section, and 44' for the total length. Below the bridge, a rectangular opening is labeled with the number 5. The drawing includes several reference numbers: 44, 30', 35', 32', 36', 44, 43, 45, 42, 8, 46', 47, 42', 43, 47', 47', 2, and 3.

JAMES C. BURGESS, OF INDIANAPOLIS, INDIANA.

RAIL TIE AND FASTENER.

1,159,742.

Specification of Letters Patent.

Patented Nov. 9, 1915.

Application filed August 2, 1915. Serial No. 43,299.

To all whom it may concern:

Be it known that I, JAMES C. BURGESS, a citizen of the United States, residing at Indianapolis, in the county of Marion and State of Indiana, have invented a new and useful Rail Tie and Fastener, of which the following is a specification, reference being had to the accompanying drawings and to the letters and figures of reference marked thereon.

This invention relates to the type of railway rail-tie that is designed to support railway rails and prevent lateral movement of the rails, the invention having reference 15 more particularly to a cast metal rail-tie having rail fasteners thereon.

An object of the invention is to provide an improved metallic railway rail-tie of such construction as to be adapted to be used instead of the wooden tie commonly made use of; a further object being to provide a metallic rail-tie and fasteners that shall be inexpensive, strong and reliable and which may be composed of cast steel or malleable iron 25 so as to be least liable to fracture under operating strains.

A further object is to provide an improved rail-tie and fasteners of such construction as to be able to secure the rails in accurately engaged position, even in case the rail fasteners accidentally become loosened.

A still further object is to provide a rail-tie and fasteners of such construction as to be enabled to brace the outer side of the rail 35 inexpensively and reliably, and permit the rails to be spliced by means of the plain splice bars and thus eliminate the expense incidental to the use of the heavier angle bars for splicing the rails together.

With the above-mentioned and other objects in view, the invention consists in a supporting rail-tie of novel construction and including the novel rail fasteners arranged in a novel manner in connection with the tie 40 proper; the invention consisting further in the parts, and combinations and arrangements of parts, as hereinafter particularly described and further defined in the accompanying claims.

Referring to the drawings.—Figure 1 is a perspective view of the complete tie and fasteners as preferably constructed; Fig. 2 is a transverse section on the plane of the line A A on Fig. 1; Fig. 3 is a longitudinal central section of the improved tie, partially 45 broken away, and track rails thereon; Fig. 4

is a fragmentary perspective view of the improved tie omitting the rail fasteners; Fig. 5 is an end elevation of the tie to which two abutting rails spliced together are connected; Fig. 6 is a perspective view of one of the rail fasteners inverted; and, Fig. 7 is a perspective view of the companion one of a pair of rail fasteners inverted.

On the different figures of the drawings, 65 similar reference characters indicate corresponding elements or features of construction herein referred to in detail.

A practical embodiment of the improved tie comprises a continuous base plate 1 of 70 suitable length and width and two upright members or side walls 2 and 3 fixed on the two longer edges respectively of the base plate, the walls preferably being uniform in thickness and height throughout. The upper 75 portions of the walls have suitable gaps therein to receive the rails and adjacent thereto two platforms 4 and 5 extend horizontally from one to the other of the walls at a suitable distance above the base plate 1, 80 one platform being fixed near one end and the other near the opposite end of the walls and a suitable distance below the plane of the top of the walls. The platform 4 has two low walls 6 and 7 on opposite ends respectively thereof, the platform 5 having similar walls 8 and 9 thereon, each fixed to the side walls 2 and 3 and extending up to the plane of the top thereof. The wall 6 with the upper portions 10 and 11 of the side 90 members 2 and 3 form one inclosure on one side of one gap, the wall 7 of the upper portions 12 and 13 of the side wall forming another inclosure on the opposite side of the gap in the side walls. The wall 8 with the 95 upper portions 14 and 15 and the side walls form another inclosure on one side of the remaining gap, the wall 9 with the upper portions 16 and 17 of the side walls of the tie forming another inclosure on the opposite side of the gap.

The platforms 4 and 5 have relatively low middle portions 18 and 19 constituting rail-seats of proper width to correspond to the width of the rail base, so that relatively 105 higher seats 20 and 21 for rail-fasteners are formed on opposite sides of the rail-seat 18 and form the bottoms of the inclosures, similar seats 22 and 23 being formed on the opposite sides of the rail seat 19, leaving 110 shoulders or abutments 24 and 25 between which to position one rail on the rail-seat

18, and shoulders or abutments 26 and 27 between which to position the other rail of the track on the rail-seat 19. One of the rail fastener seats has a bolt hole 28 therein, the companion one of the fastener seats having a bolt-hole 29 therein.

Each rail-tie includes also two pairs of rail-fasteners, the two fasteners of each pair differing slightly, one being adapted for the outer side of the rail, the other for the inner side. The outer fasteners comprise base plates 30 and 30' respectively provided with bolt-holes 31 and 31' in which bolts 32 and 32' are placed respectively, the bolts extending through the holes in the adjacent platform, the plates being of suitable dimensions and are placed upon the seats 20 and 23 and retained by the inclosure walls. The plates have slightly rounded outer end portions 33 and 33' that rest adjacent to the walls 6 and 8 respectively and afford solid bearing portions when the opposite inner end portions are slightly raised from the seats, the inner end portions having beveled under sides 34 and 34' respectively to conform to the contour of the top of the rail base flange. The top of the inner-end portion of the plate 30 has two upwardly extending flanges or ribs 35 and 36 thereon, the corresponding plate 30' having similar flanges or ribs 35' and 36' thereon to constitute rail braces of suitable length, being slightly shorter as is also the base plate of the fasteners when used in connection with a splice bar than when used directly against the web of a rail, it being preferable that the rail joints be arranged upon the ties. The inner rail-fasteners comprise plates 37 and 37' for each tie, being identically alike and having bolt holes 38 and 38' therein that receive securing bolts 39 and 39' respectively, the bolts being connected to the adjacent platforms, the plates having rounded portions 40 and 40' that are seated adjacent to the walls 7 and 9 respectively on the seats 21 and 22 respectively. The plates have beveled lower end portions 41 and 41' respectively that conform to the tops of the inner rail flanges. The plates that are used where there are no rail joints preferably are longer than those used where the rail joints are located on the tie, so as to extend to the web of the rail. It will be understood that the rails which the tie is more particularly designed to support are of the T-rail type comprising each a base 42, a web 43, and a head or top portion 44, or corresponding portions 42', 43' and 44'. Two abutting rails are spliced together by means of simple splice bars 45 and 45' secured to the webs of the rails in the usual manner by means of bolts 46, 46', 47 and 47'.

In practical use the ties are spaced apart on their road-bed according to the usual practice and the rails are placed on the rail

seats 18 and 19 respectively and without requiring to be gaged, the proper position of the rails being determined by the shoulders on the opposite sides of the rail seats which is effected by proper designing of the patterns from which to mold the ties. After the rails are placed in position the fasteners are placed in the inclosures provided for them and securely bolted therein and upon the flanges of the rails. The relative designs are such that the flanges or ribs forming the rail braces shall bear against the side of the outer one of the splice bars without interfering with the splice bolts. It will be understood that the ballast of the road-bed may be tamped under the ties and some placed on the base plate 1 of the ties. The rails being practically embedded in the ties, as will be seen, cannot become displaced even though the fastener bolts become loose, the bolts obviously being tightened occasionally, as will be understood.

Having thus described the invention, what is claimed as new is—

1. A rail-tie comprising two side walls, and two platforms fixed to the side walls below the plane of the top of the walls, each platform having two fastener-seats on opposite end portions thereof respectively and also a rail-seat between the fastener-seats that is lower than the plane of the fastener-seats, each fastener-seat having an inclosure wall thereon that is open toward the rail-seat for retaining a rail-fastener in position.

2. A rail-tie comprising two side walls, two platforms fixed to the side walls below the plane of the top of the walls and having each a rail-seat on the middle portion thereof and also a fastener-seat on each end portion of the platform that is higher than the rail-seat, each side wall having a gap in the upper portion thereof extending across the rail-seat, one end of each platform having a wall thereon that is connected to the side walls and therewith forms an inclosure about the fastener-seat that is open toward the rail-seat to retain a rail-fastener.

3. A rail-tie comprising two side walls, two platforms spaced apart and fixed to the walls, each platform having a rail-seat thereon and also two fastener-seats on opposite sides of the rail-seat that are higher than the rail-seat, each fastener-seat having an inclosure wall thereon extending at a distance from the rail-seat, and a plurality of rail-fasteners on the fastener-seats respectively and secured thereto within the inclosure walls, two of the rail-fasteners comprising each a plate having a beveled under edge extending partially over the rail-seat, the remaining rail-fasteners comprising each a base plate having a beveled under end portion extending partially over the rail-seat, the top of the beveled end portion having two ribs thereon.

4. In a rail-tie and fastener, the combination of a supporting tie comprising a base plate and two side walls on the plate, each wall having a gap in its upper portion near each end of the wall, two platforms fixed to the two side walls near the two opposite ends respectively of the walls and below the plane of the top of the walls, each platform having a rail-seat on its middle portion and two relatively higher fastener-seats on opposite sides respectively of the rail seat, the rail-seat extending through the gaps that are in the adjacent portions of the side walls, said fastener-seats being below the plane of the top of the side walls and having each a bolt-hole therein, the top of each fastener-seat having an upright low wall thereon at a distance from the rail-seat beyond said bolt-hole and connected to the upper por-

tions of the adjacent side walls to form an inclosure upon the fastener-seat, and a plurality of fastener plates arranged upon the fastener-seats respectively and extending partially over the adjacent rail-seats, each plate being retained laterally by the inclosure and having a bolt-hole therein, the outermost ones of the plates having each a plurality of upward extending ribs thereon that are above the rail-seat, and a plurality of securing bolts in the bolt-holes of the respective plates and the adjacent fastener-seat portions of said platforms.

In testimony whereof, I affix my signature in presence of two witnesses.
